UNITED STATES PATENT OFFICE.

JOSEPH SACHS, OF HARTFORD, CONNECTICUT.

AUTOMATIC ELECTROMAGNETIC TIME-SWITCH.

SPECIFICATION forming part of Letters Patent No. 689,128, dated December 17, 1901.

Application filed September 27, 1900. Serial No. 31,239. (No model.)

To all whom it may concern:

Be it known that I, JOSEPH SACHS, residing at Hartford, in the county of Hartford and State of Connecticut, have invented a new and useful Improvement in Automatic Electromagnetic Time-Switches, of which the following is a specification.

The object of my invention is to provide a means whereby electric lights, motors, or other translating devices can be automatically connected or disconnected from the source of current-supply at predetermined intervals. Such devices are known as "automatic time-switches" and in the past have consisted of clockworks which were arranged to release at certain time intervals another clockwork or spring motor mechanism which operated the circuit-controlling switches. Aside from the disadvantage due to the necessity for regular winding the many deficiencies of a spring clock mechanism of the size necessary for the operation of large switches are obvious.

In my invention I eliminate the necessity for manual winding and also provide means for the operation of the switches which are free of the disadvantage of springs. I accomplish this result by means of a proper electromagnet or motor which is connected in circuit at the desired intervals, and when so connected and energized it operates the circuit-controlling switch and at the same time effects the winding or other operation necessary to work the timing device or clock mechanism. While various arrangements of the necessary elements may be made, I have shown one in the drawing which embodies the elements of my invention.

In the drawing I have represented my invention by a diagrammatic view.

a represents a small clock which is wound by the spring b through the ratchet c, acted upon by the pawl d. One of the spindles in the train of this clock has a contact-arm e attached and so regulated that this arm makes one complete revolution every twenty-four hours. This contact-arm e coacts with the contacts f f', which by means of suitable set-screws can be located in different positions in the circle of the travel of the arm e. This is accomplished by shifting them on the curved arms g g'. By this arrangement it is possible

to regulate the time consumed by the arm e in moving from the contact f to the contact f'.

h h' are the spools of an electromagnet, having double windings and arms n and n', that are of iron and that are part of the magnetic circuit of the magnet. The two iron cores m m' of the magnet are connected together by the brass rod o, so that they move as one; but when one is pulled into its coil the other is consequently pushed out, and vice versa. The lower core m has a cross-arm p attached. One end of this cross-arm is connected by a suitable link to the operating-lever r' of the switch r, which is of the well-known knife-blade type. This switch is mounted on an insulating-base t and fastened to the iron arm n. The blade of the moving switch swings on the pivot r² and is a part of the lever r', so that a movement of the lever correspondingly causes a movement of the switch-blade in or out of its contact r³ on the base t. The other end of the cross-arm p has pivotally connected to it the pawl d. One end of this pawl engages with the ratchet c, so that a downward movement of the pawl causes the spring to be wound up, and I prefer to gear up from the spring-spindle to the ratchet, so that a slight movement of the ratchet causes quite a large movement of the spring-spindle.

Various other arrangements for winding the spring may be employed and actuated by the reciprocating movement of the core m.

The tooth of the pawl d is kept tightly against the ratchet by the spring d² pulling on the other end. The windings of the magnet are connected, respectively, to the curved sectors g and g', so that when the moving arm e comes in contact with either of the contacts f or f' the connections are such that one of the armature-coils is connected across the circuit composed of the wires s and s', which come from the source of supply and feed the lamps v with the current. The wire s', however, passes to the switch r, and the circuit is therefore controlled by its action.

s² and s³ are binding-posts.

It will be noticed that the current passing through the coil of the spool h causes an upward movement of the cores m and m' and an opening of the switch r through the arm r', while a current passing through the spool h' causes a downward movement of the cores

and a closing of the switch and also a rotation of the spring-winding ratchet.

The operation of the complete device is now as follows: The arm *e* has passed the contact *f*' and by closing the circuit of the spool *h*' closes the switch and moves the ratchet. After thus leaving the current on the circuit for a definite time the arm *e* is about to come in connection with the contact *f*. When this connection is made in the course of the arm's movement, the spool *h* will be energized and the core *m* drawn up, causing the motion to be transmitted through the arm *r*' to the switch and opening it. At the same time the pawl *d* will be raised and placed in a new position on the ratchet, so that the next downward movement rotates the ratchet. In this way it will be seen that the switch *r* is opened and closed at predetermined intervals, and the timing-clock is wound by the same energy that causes a motion of the switch.

Various modifications are possible in the arrangement of the magnets, the connection to the switch and its construction, the winding device, and the contact-arm *e* and contacts *f* and *f*'. My invention is not limited to the detail construction of any of these parts, but broadly covers the electromagnetic operation of a circuit-controller at predetermined intervals controlled by a suitable clock or other timing device, which is energized by the same energy, causing an operation of the circuit-controller.

I claim as my invention—

- 35 1. In an automatic electric-circuit controller, the combination with an electromagnetic mechanism, of a time mechanism, contact devices, electrical circuits between said contact devices and the electromagnetic mechanism, means actuated by said time mechanism to automatically operate the said circuits to the electromagnetic mechanism, an external electric circuit independent of the said circuits to the magnets, means actuated by said electromagnetic mechanism to simultaneously operate the said external circuit and wind the said time mechanism, substantially as set forth.
- 40 2. In an automatic electric-circuit controller, the combination with an electromagnetic mechanism, of a time mechanism, contact devices, electrical circuits between said contact devices and the electromagnetic mechanism, means actuated by said time mechanism to automatically operate the said circuits to the electromagnetic mechanism, an external electric circuit independent of the said circuits to the magnets, a switch in said external circuit, means actuated by the electromagnetic mechanism to operate said switch and means also and simultaneously actuated by said electromagnetic mechanism to wind the said time mechanism, substantially as set forth.
- 45 3. In an automatic electric-circuit controller, the combination with an electromagnetic mechanism, of a time mechanism, contact de-

70 vices, electrical circuits between said contact devices and the electromagnetic mechanism, means actuated by said time mechanism to automatically operate the said circuits to the electromagnetic mechanism, an external electric circuit independent of the said circuits to the magnets, a bar-switch, with an extension, and operated by the said electromagnetic mechanism, an arm connected to an end 75 of the cores of said mechanism, a link connecting the said arm and the said extension of the bar-switch whereby the switch is operated by the said electromagnetic mechanism and means actuated by the said electromagnetic mechanism to wind the said time mechanism simultaneously with the operation of said switch, substantially as set forth.

80 4. In an automatic electric-circuit controller, the combination with an electromagnetic mechanism, of a time mechanism, contact devices, electrical circuits between said contact devices and the electromagnetic mechanism, means actuated by said time mechanism to automatically operate the said circuits to the electromagnetic mechanism, an external electric circuit independent of the said circuits to the magnets, a bar-switch with an end extension, and operated by the said electromagnetic mechanism, an arm connected to an end 85 of the cores of said mechanism, a link connecting the said arm and the said extension of the bar-switch whereby the switch is operated by the said electromagnetic mechanism, and pawl-and-ratchet devices connected to the 90 said arm and time mechanism respectively whereby the said time mechanism is wound simultaneously with the operation of said switch, substantially as set forth.

95 5. In an automatic electric-circuit controller, the combination with two electromagnets, of a time mechanism, contact devices, electrical circuits between said contact devices and the two electromagnets, means actuated by said time mechanism to automatically operate the said circuits to the two electromagnets, an external electric circuit independent of the said circuits to the magnets, a bar-switch with an end extension and operated by the said two electromagnets, an arm connected to an end of the cores of said two electromagnets, a link connecting the said arm and the said extension of the bar-switch whereby the switch is operated by the said two electromagnets, and pawl-and-ratchet 105 devices connected to the said arm and time mechanism respectively whereby the said time mechanism is wound simultaneously with the operation of said switch, substantially as set forth.

110 Signed by me this 25th day of September, 1900.

115 JOSEPH SACHS.
